(57) CLAIM

I claim the ornamental design for a case with a plurality of features, substantially, as shown and described.

DESCRIPTION

FIG. 1 is a top, perspective view of the case with a plurality of features; the view showing my new design;

FIG. 2 is a front elevation view thereof;

FIG. 3 is a rear elevation view thereof;

FIG. 4 is a top view thereof;

FIG. 5 is a bottom view thereof;

FIG. 6 is a side elevation view thereof;

FIG. 7 is a side elevation view thereof;

FIG. 8 is a bottom, perspective thereof;

FIG. 9 is a top, perspective view thereof; the view showing the interior of the case; the view showing at least one divider; the view showing the case in an open position;

FIG. 10 is a top, exploded view thereof; the view showing the interior of the case; the view showing at least one divider; the view showing the case in an open position; the view showing the gasket separated from the case; and,

FIG. 11 is a top view thereof; the view showing the interior of the case; the view showing at least one divider; the view showing the case in an open position.

A description of the appearance of the article is as follows: A case with a plurality of features including pockets, a gasket, and a lockable handle.

1 Claim, 11 Drawing Sheets
